UNITED STATES PATENT OFFICE.

WILLIAM McCALLUM, OF NEWARK, NEW JERSEY, ASSIGNOR TO THE
BIGELOW CARPET COMPANY, OF CLINTON, MASSACHUSETTS.

DESIGN FOR A CARPET.

SPECIFICATION forming part of Design No. 13,257, dated August 22, 1882.

Application filed July 28, 1882. Term of patent 3½ years.

To all whom it may concern:

Be it known that I, WILLIAM McCALLUM, of Newark, in the county of Essex and State of New Jersey, have invented a new and original Design for Carpets, of which the following is a specification.

This invention relates to a new and original design for carpets and similar fabrics; and it consists in the novel grouping and configuration of parts, hereinafter more fully described.

The accompanying photograph illustrates a face view of a carpet having my new design. H is a stripe containing an ornamentation of diamond-shaped figures set on one end side by side along its upper edge, and below this row of diamond figures is a series of bars running obliquely.

The stripe G contains a panel, g, with flower-like ornamentation thereon, and also a smaller panel, f, likewise bearing flower-like ornamentation. Along the bottom of the stripe G runs a scalloped line, within which is set a series of flower-like figures. Below this line, and under the panel g, is the panel I, having a vase apparently containing a large bunch of flowering plants, and the panel J, set just below

the panel f, contains a figure resembling a thick vine with leaves and stems. The panels g and I are separated from the panels f and J by the vertical stripe h, having a zigzag or namentation along its length.

Below the stripe G runs a band, L, containing an ornamentation composed of small thickly-set rectangular figures separated at intervals by a leafy branch.

I claim—

1. The design for carpets, consisting of the band H, substantially as shown.
2. The design for carpets, consisting of the figure I, substantially as shown.
3. The design for carpets, consisting of the figure J, substantially as shown.
4. The design for carpets, consisting of the stripe G, containing figures g, f, I, J, and h, substantially as shown.
5. The design for carpets, consisting of the band H, stripe G, containing figures g, f, I, J, and h, and band L, substantially as shown.

WILLIAM McCALLUM.
